J. W. WHALEN
AUTOMATIC STOP RECORD
Filed Jan. 31, 1922

FIG. 1.

FIG. 3.

FIG. 2.

FIG. 4.

Inventor:
James W. Whalen;

By Robert W. Gaudle,
Attorney.

UNITED STATES PATENT OFFICE.

JAMES W. WHALEN, OF RICHMOND, INDIANA.

AUTOMATIC STOP RECORD.

Application filed January 31, 1922. Serial No. 532,936.

To all whom it may concern:

Be it known that I, JAMES W. WHALEN, a citizen of the United States, residing in the city of Richmond, in the county of Wayne, State of Indiana, have invented new and useful Improvements in an Automatic Stop Record for Phonographs, of which the following is a full, clear, and accurate specification and exposition.

10 The object of my present invention, broadly speaking, is to provide improvements in phonograph records or discs by which each record-disc will be provided with self-contained means whereby immediately upon the completion of the reproduction of the recorded matter the phonograph mechanism will automatically stop, said means being simple in character, effective in practice, requiring no thought on the part of the attendant for its installation, attention, or control; the same being practically inconspicuous in appearance, will not become inoperative by usage, and the production and installation cost of which will be practically

15 nil.

Other minor objects and particular advantages of the invention will suggest themselves in the course of the following description and that which is new will be correlated

20 in the appended claims.

The preferred means for carrying out the principles of my invention in a practical manner is shown in the accompanying drawings, in which—Figure 1 is a plan view of one side of a record disc, the same being taken on a reduced scale from actual size, and showing my invention in connection therewith.

Figure 2 is a cross section of a portion of a record disc, and of the needle operative therewith, the same being taken on a greatly enlarged scale from actual size, and showing my invention.

Figure 3 shows a portion of a record disc, and a portion of a needle, and showing my invention, all on a scale still further enlarged from that of Fig. 2. And Figure 4 is similar to Figure 2 but showing a slight modification thereover.

50 Similar indices denote like parts throughout the several views.

In order that the construction and the advantages of my invention may be more fully understood and appreciated I will now take up a detailed description thereof in which I

will set forth the invention as fully and clearly as I may.

Referring now to the drawings in detail: Letter A denotes the body of a record disc, the same having a central aperture B, and the peripheral edge C. Letter D denotes the label, which is concentric of the aperture B, and it is located on or imbedded into the surface of the body in the usual manner.

Letter E denotes the spiral impression line, which in fact is a single groove, commencing near the periphery C and extending inward uniformly and spirally with ever decreasing convolutions to some point near the outer edge of the label D, which is adjoining the end of the recorded matter.

At this latter point, that is at the inner terminal of the recorded matter, denoted by the letter E, there is formed into the face of the record disc a comparatively large V-shaped channel F, every point of which is equi-distant from the center, that is to say,—it is concentric with the aperture B, and it is a single endless channel and it is of the same size throughout.

Letter G denotes the reproducing needle or stylus whose lower end terminates in a point, which point travels in the recorded line E in the usual manner whereby the recorded matter on the disc is reproduced in the usual manner.

It is of course now apparent that a record disc having a channel F formed at the inner terminal of the recorded matter is the main feature of this present invention.

In practice the shape of the channel F is different from that of the lower portion of the needle, that is it is formed with a more acute angle than that of the lower portion of the needle, whereby if the lower portion of the needle be entered in the channel F then the shoulder formed by the upper end portion of the channel F will be the point with which the needle engages.

By reason of the shape of the channel F with relation to the lower portion of the needle it is apparent that the extreme point of the needle will not engage with the wall of the channel, that is to say the point of the needle will be suspended whereby it can not become damaged by engagement with the disc or record.

By reason of the shoulder of the channel F engaging so high, comparatively, upon the needle it is apparent that the result will

be that the needle will wedge into said channel F, thereby acting as a brake which very soon brings the disc record to absolute rest or stationary condition, thereby accomplishing the desideratum of this present invention.

Spiral impressions E are usually formed on both sides of the disc, as indicated in Figs. 2 and 4, but the inner terminals thereof scarcely ever come opposite to each other, therefore the record disc will not be weakened materially thereby, as is apparent in the drawings.

In some instance there is, or may be, an insert into one or both faces of the record disc, as the inserts H and I, Fig. 4, said inserts being of a different material from that of the body of the record disc, and I propose in some instances to form the channel F at the surface juncture of the material H with the body A, whereby the channel F will be half in one material and half in the other material, in which instance the material H should be such as to provide greater frictional contact with the needle than would otherwise be if the channel were all formed in the material of the body A.

I have found by actual tests that when a phonograph is operated in the usual manner that the needle G will travel centerward in the usual manner until at the end of the recorded portion E of the disc the point of the needle will drop into the channel F as soon as it leaves the spiral groove E, after which the entire mechanism of the phonograph will slow down and finally stop within one or two revolution of the disc or record.

I desire that it be understood that various changes may be made in the several details of construction herein shown without departing from the spirit of the invention and

without sacrificing any of the advantages thereof which are new and useful.

Having now fully shown and described my invention, what I claim and desire to secure by Letters Patent of the United States is—

1. A phonograph record disc having a spiral impression in its face in the usual manner, and having a V-shaped channel formed at the inner terminus of said spiral impression, said channel being formed in the face of the disc and concentric therewith and being larger in cross section than the spiral impression, the walls of said channel being at more acute angle with relation to each other than is the angle of the lower portion of the stylus, whereby the stylus will engage the walls of the channel only at the surface of the disc with the point of the stylus suspended in said channel, all substantially as shown and described.

2. A phonograph record disc having a spiral impression in its face, an insert in the face of the disc, said insert being of material different from the material of the main portion of the disc, said insert being flush with the face of the disc and extending centerward from the inner terminus of the spiral impression, there being a V-shaped channel formed at the juncture of the periphery of the insert with the body of the disc, substantially as set forth.

3. A phonograph record disc, the face of the disc being formed by two kinds of material which meet upon a line concentric with the disc, there being a V-shaped channel formed in the face of the disc with one portion of said channel formed in one material and the other portion in the other material of which the disc is composed, all substantially as shown and described.

JAMES W. WHALEN.
